Patented Nov. 6, 1917.

UNITED STATES PATENT OFFICE.

WILLIAM B. CAMPBELL, THOMAS A. BATEMAN, AND SAMUEL FRED WILSON, OF
PORTLAND, OREGON.

BALANCED DOUBLE-ACTING PUMP.

1,245,435.

Specification of Letters Patent.

Patented Nov. 6, 1917.

Application filed June 3, 1915. Serial No. 31,885.

To all whom it may concern:

Be it known that we, WILLIAM B. CAMPBELL, THOMAS A. BATEMAN, and SAMUEL FRED WILSON, citizens of the United States, 5 residing at Portland, in the county of Multnomah and State of Oregon, have invented certain new and useful Improvements in Balanced Double-Acting Pumps; and we do hereby declare the following to be a full, 10 clear, and exact description of the invention, such as will enable others skilled in the art to which it appertains to make and use the same.

This invention relates to a balanced double acting pump, and has for one of its objects the provision of a pump so constructed that the fluid in one column assists the raising of the fluid in the other column.

Another object of this invention resides 20 in the provision of a pump having its working parts so constructed and arranged, that the fluid in the columns will balance the working parts of the pump in a manner, that only such power is required as will suffice to 25 raise the fluid taken in the pump at each stroke of the pistons.

And another object of this invention resides in the provision of a pump consisting of few parts, easy to repair, thus providing 30 a cheap and durable structure.

Other objects of this invention will be hereinafter more clearly set forth in the specification, defined in the claims, and illustrated in the accompanying drawings, in 35 which,

Figure 1 is a top plan view of the invention.

Fig. 2 is a vertical longitudinal sectional view of the invention, showing the detail 40 construction and assembling of the working parts of the pump.

Referring to the drawings 1 denotes the base of the pump having arranged thereon the supporting standard 2 provided at its 45 upper end with the bearing 3. Arranged upon the supporting standard 2 and projecting laterally therefrom are the oppositely disposed central supporting frames 4 and 5, and also arranged upon the supporting standard 2 50 adjacent the bearing 3 are the laterally projecting upper frames 6 and 7.

Mounted in the central supporting frame 4 is the pump barrel 8 provided with the apertured head 9 and the annular flange 10 55 formed upon the head 9 for securing the

barrel 8 to the frame 4 in any suitable manner, and within the aperture of the head 9 of the barrel 8 are arranged the packing ring 11 and the gland 12.

Mounted within the upper supporting 60 frame 6 is the discharge tube 13 having the annular flange 14 at its upper end for suitably securing the tube 13 upon the frame 6. The discharge tube 13 is positioned above the barrel 8 and extends downwardly in the 65 direction of the barrel 8 but terminates at a point slightly above the head 9 of the barrel 8. Suitably secured to the flange 14 of the discharge tube 13 is one of the fluid columns 15, shown in dotted lines. 70

Mounted in the central supporting frame 5 is the pump barrel 16 provided with the apertured head 17, and the annular flange 18 upon the head 17 for securing the barrel 16 upon the frame 5 in any suitable manner, 75 and within the aperture of the head 17 of the barrel 16 are arranged the packing ring 19 and the gland 20.

Mounted within the upper supporting frame 7 is the discharge tube 21 provided 80 with the annular flange 22 at the upper end thereof for securing the discharge tube 21 upon the frame 7 in any suitable manner. The discharge tube 21 is positioned above the barrel 16 and extends downwardly in 85 the direction of the barrel 16 but terminates at a point slightly above the head 17 of the barrel 16. Suitably secured to the flange 22 of the discharge tube 21 is another fluid column 23, shown in dotted lines. 90

The barrels 8 and 16 are of greater diameter than the opening or aperture in the respective heads 9 and 17, the opening or aperture in the heads 9 and 17 are also of greater diameter than the discharge tubes 95 13 and 21 for the purposes hereinafter described.

Operatively interposed between the barrel 8 and the discharge tube 13 is the hollow piston 24 slidably mounted within the packing gland of the head 9 of the barrel 8 and upon the exterior surfaces of the discharge tube 13. This hollow piston 24 is formed with the head 25 having arranged therein an opening approximately equal to the diameter of the discharge tube 13, the head being further provided with the packing ring 26 and the gland 27 for providing a tight joint between the exterior surfaces of the discharge tube 13 and the head 25 of the piston 105 110

24 which surrounds the discharge tube 13 and is slidably mounted thereon. The lower end of the piston 24 which operates within the barrel 8 is provided with the spider like 5 apertured valve seat 28 upon which is adapted to be seated the valve 29 operating within the lower portion of the piston 24. The valve 29 is slidably mounted upon the upper portion of the stem 30 which projects 10 into the lower portion of the piston 24 and retained thereon by the lock nut or head 31. The stem 30 is fixedly mounted by any suitable means in the centrally apertured portion 32 of the spider of the valve seat 28, 15 and extends downwardly through the centrally apertured portion 33 of the spider like member of the apertured piston head 34, in which centrally apertured portion 33 the stem 30 is fixedly mounted and retained 20 therein by the lock nut or head 35. The upper surface 36 of the piston head 34 provides a valve seat upon which is adapted to be seated the valve 37, the valve 37 being slidably mounted upon the lower portion of the 25 stem 30 and capable of reciprocatory movement upon the stem 30 between the valve seat 36 of the piston head 34 and the bottom surface of the lower end of the piston 24.

Operatively interposed between the barrel 30 16 and the discharge tube 21 is the hollow piston 38 slidably mounted within the packing gland of the head 17 of the barrel 16 and upon the exterior surfaces of the discharge tube 21. This hollow piston 21 is 35 formed with the head 39 having arranged therein an opening approximately equal to the diameter of the discharge tube 21, the head being further provided with the packing ring 40 and the gland 41 for providing 40 a tight joint between the exterior surfaces of the discharge tube 21 and the head 39 of the piston 38 which surrounds the discharge tube 21 and is slidably mounted thereon. The lower end of the piston 38 which operates 45 within the barrel 16 is provided with the spider like apertured valve seat 42 upon which is adapted to be seated the valve 43 operating within the lower portion of the piston 38. The valve 43 is slidably mounted 50 upon the upper portion of the stem 44 which projects into the lower portion of the piston 38 and retained thereon by the lock nut or head 45. The stem 44 is fixedly mounted by any suitable means in the centrally apertured portion 46 of the spider of the valve seat 42, and extends downwardly 55 through the centrally apertured portion 47 of the spider like member of the apertured piston head 48, in which centrally apertured portion 47 the stem 44 is fixedly mounted and retained 60 therein by the lock nut or head 49. The upper surface 50 of the piston head 48 provides a valve seat upon which is adapted to be seated the valve 51, the valve 65 51 being slidably mounted upon the lower

portion of the stem 44 and capable of reciprocatory movement upon the stem 44 between the valve seat 50 of the piston head 48 and the bottom surface of the lower end of the piston 38.

For actuating the hollow pistons 24 and 38, the pistons each have formed upon the exterior portions of their heads 25 and 39 at diametrically opposite points the trunnions 52 and 53 respectively, and pivotally 70 connected to the trunnions 52 of the piston 24 at their lower ends are the links 54, and likewise pivotally connected to the trunnions 53 of the piston 38 at their lower ends are the links 55. The upper ends of the links 54 80 are pivotally connected as at 56, to the respective side bars 57 of an oscillating frame, and the upper ends of the links 55 are also pivotally connected as at 58 to the respective side bars 57. The side bars 57 of the oscillating frame are arranged in parallel relation to each other and have their central portions pivotally mounted upon the projecting ends of the shaft 59 which is mounted in the bearing 3 at the top of the support 85 standard 2. The ends of the bars 57 of the oscillating frame adjacent the pivotal points 56 of the links 54 are connected together by the yoke 60 which has secured centrally thereon the handle 61 for actuating 90 the oscillating frame for operating the pump. The free ends of the bars 57 of the oscillating frame adjacent the pivotal points 58 of the links 55 may also be connected together with a yoke provided with an operating handle similar to the yoke 60 and handle 61 if desired.

The operation of the pump is as follows:—

By referring to Fig. 2 of the drawings, 105 and assuming that the pump has been in continual operation for a sufficient length of time to be now forcing the fluid therethrough, the parts at the right hand side of the pump are shown in the position which 110 they assume when the fluid is being discharged from the upper portion of the barrel 8 into the piston 24 around the valve 29 as indicated by the arrows, while the parts at the left hand side of the pump are shown 115 in the positions which they assume when the fluid is being taken in from the lower portion of the barrel 16 into the upper portion of the barrel 16 through the piston head 48 and around the valve 51 as indicated by 120 the arrows. The manner in which the fluid is forced upwardly through the pump will be more clearly understood by assuming that the parts at the right hand side of the pump have previously been in the position of the 125 parts shown at the left hand side of the pump, with the valve 29 being closed in the manner of the valve 43 and the valve 37 being open in the manner of the valve 51, whereby upon the upward movement of the 130

piston 24 the force of the fluid then contained in the upper portion of the barrel 8 will immediately seat the valve 37 upon the valve seat 36 of the piston head 34, and upon the further upward movement of the piston 24 carrying with it the piston head 34 through the medium of the connecting stem 30, the fluid in the upper portion of the barrel 8 will be compressed between the upper surface of the piston head 34 and its valve 37 and the inner surface of the head 9 of the barrel 8 and the under surface of the piston 24 and its valve 29. The compression of the fluid between these parts is increased in intensity as the respective piston 24 and piston head 34 continues to move upwardly until the compression of the fluid reaches a point sufficient to overcome the weight of fluid in the adjacent column whereupon the force of the compressed fluid will elevate the valve 29 from its seat 28 and upon the upper portion of the stem 30 and the fluid in the upper portion of the barrel 8 rushes through the ports of the valve seat 28 around the valve 29 into the piston 24 as indicated by the arrows, and this inflow of the fluid continues until the working parts at the right hand side of the pump have reached their uppermost positions. After these parts at the right hand side of the pump have reached their uppermost limit, having been drawn upwardly by the right hand side of the oscillating frame through the medium of the link connections 54 with the piston 24, the parts are now caused to descend by the reverse movement of the oscillating frame and the moment that the piston 24 begins to descend, the weight of the fluid in the piston 24, the discharge tube 13 and the fluid column 15 automatically seats the valve 29 against the valve seat 28 thereby closing the ports therein, and through the medium of the connecting stem 30 the piston head 34 is forced downwardly simultaneously with the piston 24, and owing to the force exerted upon the under side of the valve 37 by the fluid contained in the lower portion of the barrel 8, the valve 37 is raised upwardly upon the stem 30 and assumes the position of the valve 51 at the left hand side of the figure, whereupon the fluid beneath the piston head 34 now freely passes through the ports thereof and around the valve 37 in a manner indicated by the arrows in the ports of the piston head 48 at the left hand side of the pump, and the fluid thereby enters and fills the area in the upper portion of the barrel 8 in the same manner that the area in the upper portion of the barrel 16 is filled, and when the piston 24 is again raised in the manner above described, repetition of the operation takes place.

Of course, it is to be understood that the working parts at the right hand side of the

pump, and the working parts at the left hand side of the pump operate alternately with each other; therefore, the mode of operation above and primarily described relative to the parts at the right hand side of the pump are equally applicable to the mode of operation of the parts at the left hand side of the pump, as these respective parts are constructed and operate in a similar manner but are only actuated alternately.

It will further be seen from the above described construction and operation of the pump that the same is constructed in a manner whereby the weight of the fluid in the respective fluid columns 15 and 23, the discharge tubes 13 and 21, and the pistons 24 and 38 not only automatically seats the respective valves 29 and 43 immediately after the discharge of the fluid from the barrels or cylinders 8 and 16 into the pistons 24 and 38 respectively, but the weight of the fluid against the valves 29 and 43 and the valve seats 28 and 42 of the respective pistons 24 and 38 thoroughly balances the working parts at each side of the pump, the weight of the fluid in one column counterbalancing the weight of the fluid in the other column. Therefore, the only power required for pumping the fluid to any desired point of discharge is that sufficient to force the weight of the fluid taken in at each alternate stroke of the pistons of the pump.

While the preferred embodiment of the invention has been herein shown and described, minor alterations and variations may be made therein to meet the exigencies of the case without departing from the spirit of this invention or the scope of the claims.

Having described our invention what we claim as new and desire to secure by Letters Patent, is:—

1. A pump, comprising a support, open ended barrels centrally mounted upon said support and provided with heads, discharge tubes mounted upon said support in superposed relation to said barrels, fluid columns connected to said discharge tubes, hollow pistons slidably mounted upon the exterior of said discharge tubes and within the heads of said barrels for operating within said barrels, disks within said barrels operatively connected to said pistons, valves and valve seats upon said hollow pistons and said disks, and means for alternately actuating said hollow pistons and said disks.

2. A pump, comprising a support, open ended barrels centrally mounted upon said support and provided with heads, discharge tubes mounted upon said support in superposed relation to said barrels and of less diameter than the diameter of said barrels, fluid columns connected to said discharge tubes, hollow cylindrical pistons of less diameter than said barrels but of greater diameter than said discharge tubes slidably

65 75 80 85 90 95 100 105 110 115 120 125 130

4

mounted upon the exterior of said discharge tubes and within the heads of said barrels for operating within said barrels, apertured disks within said barrels operatively connected with said pistons and coacting therewith, coacting pairs of valves and valve seats upon said hollow cylindrical pistons and said apertured disks, and means for alternately actuating said pistons and said coacting disks within said barrels.

- 10 3. A pump, comprising a base, a supporting standard thereon, central supporting frames upon said standard, upper supporting frames upon said standard, a bearing 15 upon the upper end of said standard, an operating frame pivotally mounted upon said bearing, a barrel mounted in each of said central frames, a discharge tube mounted in each of said upper frames, a fluid column 20 connected to each of said discharge tubes, a hollow piston slidably mounted in each of the heads of said barrels and operating therein, the heads of said pistons slidably embracing the exterior surfaces of said discharge tubes, links connecting said pistons 25

with said operating frame and actuated thereby, a valve seat in the bottom of each of said pistons, a connecting stem fixedly mounted in each of the valve seats of said pistons and projecting from each side thereof, a valve slidably mounted upon said stem in each of said pistons for opening and closing said valve seats, a piston head operating in each of said barrels and secured upon the lower end of the respective stems and movable simultaneously with said pistons, a valve seat in each of said piston heads, and valves slidably mounted upon said stems for opening and closing said valve seats of said heads.

40 In testimony whereof we have signed our names to this specification in the presence of two subscribing witnesses.
